(57) **CLAIM**

The ornamental design for a storage container, as shown and described.

DESCRIPTION

FIG. 1 is an isometric view of a storage container showing our new design.

FIG. 2 is a top view thereof.

FIG. 3 is a bottom view thereof.

FIG. 4 is a left side view thereof.

FIG. 5 is a right side view thereof.

FIG. 6 is a back view thereof; and,

FIG. 7 is a front view thereof.

The broken lines shown in the Figures show portions of the storage container that form no part of the claimed design. The shade lines in the Figures show contour and do not claim surface ornamentation or treatment.
